FRANK A. WELLS. OF MEMPHIS, TENNESSEE.

Letters Patent No. 96,177, dated October 26, 1869.

IMPROVEMENT IN COTTON-SEED HULLING-MACHINES.

The Schedule referred to in these Letters Patent and making part of the same.

To all whom it may concern:

Be it known that I, FRANK A. WELLS, of Memphis, in the county of Shelby, and State of Tennessee, have invented a new and improved Cotton-Seed Huller; and I do hereby declare that the following is a full, clear, and exact description thereof, which will enable others skilled in the art to make and use the same, reference being had to the accompanying drawings, forming part of this specification.

The object of this invention is to provide a cotton-seed huller, more efficient in operation, less liable to clog or be damaged by foul or hard substances, and better adapted for adjustment of the cutters of the concave shell than the machines now in use.

It is also intended to provide a more economical arrangement of the cutters, in respect of grinding them.

Figure 1 represents a transverse sectional elevation of my improved machine, and

Figure 2 represents a plan view of the same.

Similar letters of reference indicate corresponding parts.

A represents the revolving cylinder, the cutters B of which consist of steel or chilled plates, concaved on both sides, and ground square on the edges, and placed in suitable recesses in the cylinder, pitched at the proper angle to give the best results in action with the cutters of the shell, and adapted for turning the said cutters B, so as to use all the corners thereof successively, as they become worn.

The concave shell is composed of knives C and dividing-plates D.

The dividing-plates are arranged in a circular clamp, E, and in circular supports in the side-frames of the machine.

These end supports F are provided with set-screws G, screwing against both the outer and inner edges of the cutters, for adjusting them to or from the cylinder, or the cutters thereof.

The cutters of the concave are made with edges at right angles to the sides, so that they, too, may be

changed, to utilize all the corners as cutting-edges, and they are set at an angle with the radial lines of the cylinder, to present the corners more acutely in the direction of the cutters of the cylinder.

The cylinder is revolved in the direction indicated by the arrow, and thereby the work is much more uniformly accomplished, as all the seeds are brought between the edges of the cutters, whereas, if revolved the other way, many of the seeds would be crowded into the lowest part of the recesses, at the rear of the cutters of the cylinder, and thereby escape the actions of the cutters, also clogging the machine to a considerable extent.

Another important advantage of running in this direction is, that heavy and hard substances, such as stones, iron, &c., will not be carried in between the cylinder and the concave, unless quite small, but will remain on the top of the cylinder, in front of the concave, from where they may be removed readily.

Having thus described my invention,

I claim as new, and desire to secure by Letters Patent—

1. The cylinder A, having knives B, shaped and applied as specified, in combination with the corresponding knives C, of the concave shell, all operating together, substantially in the manner described.

2. The combination of revolving knives B with cutters C, arranged at a pitch below the centre of the cylinder, and having an independent radial adjustment, by means of set-screws or their equivalents, substantially as set forth.

3. The improved concave clamp E, provided with means for the separate adjustment of each square-ended tool, with its cutting-edge at a pitch below a radial line, and removable at the extremities of the concave, all as shown and described.

FRANK A. WELLS.
